METHOD AND MEANS FOR AFFIXING AD-
VERTISING SEALS TO NEWSPAPERS AND
OTHER PRINTED MATTER

Wilhelm Schöler, Brunn, Czechoslovakia

Application January 4, 1937, Serial No. 118,972

7 Claims. (Cl. 216—21)

My invention relates to newspapers, magazines, folders and other printed matter and more particularly to the sealing of such articles for mailing purposes, or the like. The principal object of the present invention is to devise a method and means for rapidly applying a seal to each newspaper, magazine, folder, and the like in an economic manner, while the article is being conveyed from the folding mechanism to a place of delivery.

A further object of this invention is to apply a seal which can be used at the same time for advertising purposes.

Another object of my invention is to produce a seal which securely holds the pages of the printed matter together so that they won't become torn or otherwise mutilated.

With all these and other objects in view, my invention consists in a practical method and means for accomplishing the various objects simply and conveniently and without any waste of the material used for the seal.

For a fuller understanding of my invention, I refer to the annexed drawing, in which I have diagrammatically illustrated the new method and the means for carrying it into effect. In this drawing, Fig. 1 shows a part of the folding mechanism for delivering the folded newspapers, magazines, folders or the like to the endless conveyor. Fig. 2 is a side-view of one of the endless belts constituting the conveyor, of the rolls carrying the webs or tapes which form the seals and the moistening or glue-applying devices therefor; Fig. 3 is a detail view of the spring-controlled rolls for sealing the tapes in place; Fig. 4 a view of two sets of rolls used respectively for indenting the sealing tapes and for severing them at given intervals; Fig. 5 shows a seal as applied to the corner of a folded newspaper.

In the appended drawing, the method and means shown therein are supposed to be used for applying a seal to a folded newspaper.

At 1 in Fig. 1 is indicated a delivery roll such as used in connection with the folding mechanism of a rotary press, which roll is equipped with forks shown at 2. These forks, as will be seen, are disposed along a slant so that the folded newspaper, shown at 3, will be held in the position shown in Fig. 1, in which position one of the corners of the folded paper projects outwardly, as shown at 4. At 5 in Fig. 1 is shown a stop to prevent the newspaper from dropping out of the delivery roll. From this delivery roll, the newspapers reach the conveyor indicated at 6 in Figs. 2, 3 and 4, and composed of a plu-

rality of mutually spaced endless belts travelling parallel with each other. Onto this conveyor the folded newspapers are delivered by the delivery roll 1 in overlapping successive arrangement, with their corners 4 projecting from one side of the conveyor. In the same vertical plane of the projecting newspaper corners 4 are provided two spools shown at 7 and 8 disposed respectively above and below the horizontal plane of the conveyor. These spools each carries a narrow web of paper or other suitable material, indicated at 9 and 10 respectively. At 11 and 11' and 12 and 12' respectively are indicated in opposed relationship spring controlled rolls, between which pass the projecting corners 4 of the newspapers and between which are guided the two narrow webs of paper 9 and 10, one above and the other below the newspaper corners to be pressed thereagainst by the said spring-controlled rolls 11, 11' and 12, 12'.

At 13 and 14 are indicated moistening means, comprising a set of rolls 13^a, 13^b, 13^c and 14^a, 14^b, 14^c respectively whereby a sufficient amount of moisture is applied to the gummed sides of the narrow webs 9 and 10. When these webs of paper are not gummed, there may be substituted for the moistening means a similar means whereby a liquid adhesive is applied to the one side of the paper webs 9 and 10.

In Fig. 4 are shown two additional sets of rolls, provided along the conveyor 6 carrying the newspapers to be sealed. At 15 and 16 in said figure are shown two superposed narrow rolls, which along a portion of their circumference are provided with teeth, as shown at 15' and 16', which teeth, upon the rotation of said rolls cooperate to produce indentations in the narrow paper webs where these project beyond the corners 4 of the newspaper. Further on along the conveyor 6, there are provided in superposed relation two rolls shown at 17 and 18, one of which rolls is provided in its circumference with spaced apart cutters as indicated at 17^a, 17^b, 17^c, 17^d, while the other roll (18) is provided along its circumference with correspondingly spaced apart recesses 18^a, 18^b, 18^c, 18^d to receive the said cutters.

In Fig. 5 of the drawing is shown a portion of a newspaper with its corners closed by a seal 21 produced in accordance with my invention by the method and means herein described.

The method, as will appear from the drawing, is carried into effect as follows:

The newspapers, as they come from the folding means of a rotary press, are engaged by

the slantingly disposed forks 2 of the delivery roll so as to be positioned as shown in Fig. 1 of the drawing with one corner projecting. Being thus one by one delivered to the conveyor 6, the newspapers also project with one corner beyond the edge of the conveyor. The narrow webs of paper 9, 10 carried by the spools 7 and 8 are continuously drawn from these spools by means not shown so as to travel along the edge of the moving conveyor 6, over which the corners of the newspapers project in alinement with these corners and in engagement therewith, both from above and from below the same. As the projecting corners of the newspapers together with the two webs of paper pass between the spring-controlled rolls 11, 11' and 12, 12', the webs 9 and 10 having previously been moistened if gummed, or supplied with an adhesive by the devices shown in Fig. 2 at 13 and 14, are pressed by the said rolls into firm contact with the projecting corners of the newspapers, which corners, as shown in the drawing, are sufficiently spaced apart to permit portions of the webs on either side of the corner of the newspaper to be glued together. At these places the webs are subsequently cut, which may be done either by hand or by mechanically operated cutters, such as shown for instance in Fig. 4.

Where it is desired to produce a still firmer hold between the contacting webs intermediate the projecting corners of the newspapers, as may be necessary when the thickness of the matter to be sealed is great, the corners of the newspapers, or other printed matter, are passed together with the sealing webs through further rolls, shown at 15 and 16 in Fig. 4. These rolls, as will be seen, have portions of their circumference formed or provided with teeth so arranged, that they will engage the webs at the places intermediate the projecting corners to be sealed, producing indentations in said webs causing them to more firmly adhere to each other than when merely pressed against each other by the spring-controlled rolls 11, 11' and 12, 12' shown in Fig. 2.

After the projecting corners and the sealing webs of paper have passed either between the spring-controlled rolls 11, 11' and 12, 12' or between the toothed rolls 15, 16, they are fed between cutting means, as for instance a cutter carrying roll 17 and a recessed roll 18 shown in Fig. 4. The speed of travel of the conveyor is so timed relative to the speed of rotation of the two rolls 17 and 18, that the four cutters of roll 17 shown at 17^a, 17^b, 17^c and 17^d in Fig. 4 and the corresponding recesses 18^a, 18^b, 18^c and 18^d in roll 18 will cooperate with each other when the glued-together webs intermediate the corners to be sealed reach the position shown at the right in Fig. 4. At 21 in Fig. 5 is shown a finished seal.

The webs of paper, or other suitable material, used for producing the seals may carry printed matter on the outside, which may be used for advertising purposes. As the portions of the webs will adhere to the newspaper or other printed matter, even after the portions of the seal have been separated to afford full access to the reading matter, the advertising matter will remain intact.

An obvious advantage of my new method is that the newspapers or other printed matter can be sealed while being delivered from the printing press without any interruption in the operation of the press, as the narrow webs of paper,

or other material used for producing the seals can be fed along the conveyor 6 with the same speed with which the latter travels. The spools 7 and 8 are made of a size to carry webs of sufficient length for even a very large edition, and, moreover, the spools can be made to be quickly exchanged or replaced.

I claim:

1. A method of affixing advertising seals to newspapers and other printed matter comprising continually feeding the individual copies of the printed matter in succession with one of their corners projecting beyond the line of feed, feeding in close alinement with said projecting corners above and below the same a web of paper, or the like, printed on one side, fastening said webs to said projecting corners from either side thereof and to each other, and severing the webs of paper intermediate the projecting corners.

2. A method of affixing advertising seals to newspapers and other printed matter, comprising continually feeding the individual copies of the printed matter in succession with one of their corners projecting beyond the line of feed, feeding in close alinement with said projecting corners, above and below the same, a web of paper, or the like, gummed on one of its sides and printed on its other side, moistening the gummed sides of said webs, pressing the gummed sides against the projecting corners from either side thereof and against each other, and severing the webs of paper intermediate the projecting corners.

3. A method of affixing advertising seals to newspapers and other printed matter, comprising continually feeding the individual copies of the printed matter in succession with one of their corners projecting beyond the line of feed, feeding in close alinement with said projecting corners, above and below the same, a web of paper, or the like, printed on one side, applying an adhesive to the other sides of said web, pressing these sides of the webs against the projecting corners from either side thereof and against each other, and severing the webs of paper intermediate the projecting corners.

4. A method of affixing advertising seals to newspapers and other printed matter, comprising continually feeding the individual copies of the printed matter in succession with one of their corners projecting beyond the line of feed, feeding in close alinement with said projecting corners, above and below the same, a web of paper, or the like, printed on one side, and treated with an adhesive on the other side, securing said webs with their treated sides to the projecting corners from either side thereof, and to each other indenting the portions of the webs intermediate the corners and severing the webs across their indented portions.

5. In combination with means for positioning printed matter with one of its corners projecting to one side, a conveyor for continuously feeding the printed matter along in succession with the projecting corner extending beyond the line of feed, means for feeding to the projecting corners in close alinement therewith, both from above and below, a printed web of paper, or the like, means for applying to the unprinted sides of said webs of paper an adhesive, means for yieldingly pressing said webs to the projecting corners, from either side thereof, and against each other, and means for severing said webs intermediate the projecting corners.

6. In combination with means for positioning printed matter with one of its corners projecting to one side, a conveyor for continuously feeding the printed matter along in succession with the projecting corner extending beyond the line of feed, means for feeding to the projecting corners in close alinement therewith, both from above and below a web of paper, or the like, gummed on one side and printed on the opposite side, means for applying moisture to the gummed side of said webs, means for yieldingly pressing the moistened gummed sides of the webs against the projecting corners, from either side thereof, and against each other, and means for severing the webs intermediate the projecting corners.

15 7. In combination with means for positioning

printed matter with one of its corners projecting to one side, a conveyor for continuously feeding the printed matter along in succession with the projecting corner extending beyond the line of feed, means for feeding to the projecting corners in close alinement therewith, both from above and below, a web of paper, or the like, treated on one of its sides with an adhesive and printed on its other side, means for yieldingly pressing the treated side of the webs against the projecting corners, from either side thereof, and against each other, means for indenting the pressed together portions of the webs, and means for severing the webs along said portions intermediate the projecting corners.
